UNITED STATES PATENT OFFICE.

DALE P. CARTWRIGHT, OF FORT WAYNE, INDIANA, ASSIGNOR TO FRIGIFAX MANUFACTURING COMPANY, OF LA FAYETTE, INDIANA, A CORPORATION OF INDIANA.

GAS-PURIFYING DEVICE.

1,181,435.

Specification of Letters Patent.

Patented May 2, 1916.

Application filed September 28, 1914. Serial No. 863,859.

To all whom it may concern:

Be it known that I, DALE P. CARTWRIGHT, a citizen of the United States of America, residing at city of Fort Wayne, county of 5 Allen State of Indiana, have invented certain new and useful Improvements in Gas-Purifying Devices, of which the following is a specification.

My invention relates to an improvement 10 in devices adapted to be used in connection with a compressed gas refrigerating system.

The device is intended to be interposed in the conduit conveying the gas or fluid under pressure.

15 The object of my invention briefly stated is to provide means whereby substance foreign to the ammonia or other gas may be precipitated before it passes through the controlling valve and collected in a reservoir 20 from whence it may be drained, thus delivering the gas relieved of such impurities.

I have illustrated my invention in the accompanying drawing which is a vertical section of two valves.

25 1 indicates a valve seat and 2 a valve stem adapted to register with said valve seat, 3 is a port leading to the valve and 4 is an exhaust port therefrom.

5 is an annular chamber surrounding the 30 valve seat 1, the base of which is at a level lower than that of the valve seat 1.

6 is a valve seat and 7 a stem for the same, while 8 is an exhaust port leading from the base of the annular chamber or reservoir 5 35 to drain said reservoir when said stem is withdrawn to open the valve 6.

I have found in the operation of a refrigerating system such as that described that the ammonia coming from the 40 compressor carries in suspension certain foreign bodies which are heavier than the ammonia, and will be precipitated when the fluid is at rest or not in active flow. This is the normal condition of the ammonia as it 45 stands before the valve in the port 3. In view of the fact that the reservoir 5 is of a lower level than the valve seat 1, such foreign matter will fall into said reservoir

and remain there, while the lighter fluids will pass through the retaining valve under 50 pressure. This accumulation when continued for a period of time will fill said reservoir 5 when by opening the port 8 through the valve 6, such accumulation will drain or be blown off. 55

My invention therefore consists in providing a reservoir adjacent the valve and at a lower level thereto.

I do not intend to limit myself to the particular structures shown but claim my improvement in whatever form it may be embodied. 60

What I claim is:

A compressed gas purifying device for refrigerating systems embodying a casing 65 provided with an interior chamber, inlet and exhaust ports, the exhaust port being of less area than the inlet port for insuring the flooding of the chamber, and both of which ports are positioned above the base of the 70 chamber whereby a reservoir is formed in which is deposited the precipitants which separate from the gas as such gas passes through the chamber, and a valve coöperating with the exhaust port, independently 75 of the inlet port, for regulating the passage of gas through the exhaust port while the inlet port is left unobstructed, in combination with a draw-off duct at the base of the chamber, leading out of the chamber 80 and out of the system with which the device is associated, for allowing of the scavenging of the precipitants out of the system irrespective of the position of the valve which controls the exhaust port, and a normally 85 closed, manually operable valve for controlling the draw-off duct, whereby the reservoir may be scavenged without interrupting the circulation of the gas through the refrigerating system. 90

Signed by me at Fort Wayne, Indiana, this 17th day of September, 1914.

DALE P. CARTWRIGHT.
